UNITED STATES PATENT OFFICE

169,266

CLOSURE CAP FOR A FLUID CONTAINER
SPOUT

Herman M. Lehmann, Seattle, Wash.

Application February 9, 1952, Serial No. 18,453

Term of patent 14 years

(Cl. D58—26)

To all whom it may concern:

Be it known that I, Herman M. Lehmann, a citizen of the United States, residing at Seattle, in the county of King, State of Washington, have invented a new, original, and ornamental Design for a Closure Cap for a Fluid Container Spout, of which the following is a specification, reference being had to the accompanying drawings, forming a part thereof.

Fig. 1 is a side elevation view of a closure cap for a fluid container spout embodying my new design.

Fig. 2 is a top view of the cap.

Fig. 3 is an edge view of the cap.

I claim:

The ornamental design for a closure cap for a fluid container spout, as shown.

HERMAN M. LEHMANN.
